FRANZ LANG, OF STUTTGART, GERMANY.

FUEL PUMP.

Application filed August 4, 1925, Serial No. 48,168, and in Germany April 18, 1922.

Fuel pumps for combustion power engines with fuel injection are known in which, for regulating the quantity of the fuel injected the moment of opening an overflow-valve is adjusted by the speed regulator. These pumps are characterized by the feature, that a lug or stop connected to the pump piston opens the overflow-valve by means of a double lever shortly before the end of the suction stroke so that said valve closes again only shortly after the beginning of the pressure stroke of the pump, and that in the latter course of said pressure stroke a second lug or stop, connected to the pump piston or to the driving means of the same and being adapted to be adjusted by the speed regulator, again opens the valve.

The purpose of this arrangement is to feed in the desired moment of the injection the fuel in considerable quantity and with high speed to the injection nozzle.

The consequence of this per se desirable aim is however, that at the closing of the injection nozzle the fuel still present on the valve seat must be removed by force in order to enable at all the necessary rapid closing of the nozzle-valve.

In contradistinction to this arrangement the seat of the nozzle-valve shall be released from fuel by means of the fuel pump according to the present invention always immediately before the closing of the valve, so that the nozzle can take its seat without being forced of first removing the fuel from said seat. Furthermore this construction enables in the most safe manner the regulation of the feeding of very small quantities of fuel.

This purpose is mainly attained by arranging the overflow-valve to the suction space in the pressure pipe between pump pressure valve and injection valve and by opening said overflow-valve during the last part of the pump pressure stroke. Thereby the surplus compressed fuel is operatively returned to the pump suction space always before the pump piston reaches its upper dead center position, so that the fuel quantities present in the pressure pipe constantly receive a pulsating motion.

The return feed of the surplus compressed fuel can be effected by a spring-influenced valve arranged axially above or below the fuel pump, by a separate piston

or by a piston formed by an extension of the pump piston, said extension being provided with a circular groove, and the guide space of said piston extension being connected at one side to the pressure space and at the other side to the suction pipe and to the suction space of the fuel pump.

Further it may be mentioned, that combustion power engines are known, in which a partial draining or emptying of the fuel pipe is enabled by means of a return flow-valve, however only in view of the fact that the retort pressure can act through the open nozzle upon the liquid in the pipe.

As this present action does not take place, when the nozzle is closed, at first it must appear useless to an expert to provide an overflow-valve in fuel pumps for injection engines with closed nozzle.

Only the exact knowledge of the pressure action in the fuel piping, namely the breathing of the same under the influence of the motion proceedings has led to the idea of employing a return flow-valve in the mentioned manner also with closed nozzles and has rendered it possible to govern exactly the injecting operation as well in regard to the time as also in regard to the quantity.

In the accompanying drawing, in which several forms of construction of the subject matter of my invention are illustrated.

Fig. 1 shows a vertical section of a fuel pump with the injection nozzle in the cylinder head.

Figs. 2 and 3 show two modifications, in which the injection nozzle is omitted and

Fig. 4 shows the adjustment of the pump piston, which adjustment can be effected by the engine regulator or by hand.

In Fig. 1 *a* indicates the cylinder head, to which the nozzle body *b* is rigidly connected. *c* indicates the nozzle needle, which carries a spring seat *d*, upon which the lower part of the spring *e* rests (the adjusting means being omitted as immaterial).

The fuel pump body *f* is provided with a suction valve *g* and a pressure valve *h* of any desired known construction and is further provided in the extension of the bore of the piston *i* with an equalizing valve *k*, which is reduced in cross-section behind the tightening surface by turning, said valve being lifted by the piston *i* before the latter reaches its dead center po-

sition. An adjustable spring *l* effects the closing of this valve. Fuel dripping from the hollow space provided above the nozzle needle *c* in the body *b* is fed through the pipe *m* to the suction pipe *g'* of the pump *f* at each change of the stroke. In order to enable an exact regulation of the pressure in this pipe at a not natural drop of the fuel, a reduction valve *n* is arranged in the pipe. 10 On the other side the reduced portion of the equalizing valve *k* is connected to the pressure pipe *h'* of the pump *f*. An arising excess pressure accordingly opens the valve *k* and effects partially a draining or emptying of the pressure chamber. The overflowing fuel is subjected to the sucking action, while a further flow of the fuel is fully obviated.

In Fig. 2 the overflow-valve is connected 20 between valve seat and suction space to a fairly tight-fitting valve body *k'*, the stem of which also is partially turned down or reduced. When now the valve with the piston is suddenly lifted by the pump piston, a sucking action on the fuel present in the pressure pipe is produced. When the spring *l* again tends to close the valve, the fuel trickles down through the very small intermediate space between the piston and the 25 slide surface. The pipe *m* serves for the same purpose as in Fig. 1.

In Fig. 3 this piston is replaced by a simple extension of the piston *i* with a circular groove *i'* serving as a regulating edge, 30 said groove being connected to the pressure pipe *h'* by means of a second pipe *h''*. The mode of operation is the same, but the production is more simple and economical.

Fig. 4 illustrates the possibility of putting 40 the before described devices preliminarily out of operation during the starting of the motor and of making the operation of the fuel pump dependent of the regulator of the engine, when the condition of persistence 45 of the latter has been reached, however it is also always possible to correct the operation of the fuel pump by hand. The fuel piston *i* which is operated by any desired known cam or eccentric devices, carries at the end, which 50 is directed away from the pump a screw thread *n* and also a rigidly connected gear wheel *o*. The thread *n* can be influenced on the tappet guide *p* by a tooth bar operated by the regulator of the motor or by hand. 55 During the starting of the motor the piston *i* is still sufficiently distant from the equalizing members *k* in case 1, *k'* in case 2 and not sufficiently closing the circular groove *i'* in case 3. The starting period is burdened 60 by a somewhat greater consumption of fuel, which however is materially lessened at the engagement of the regulator. The correction by hand is especially important in ship- and traction-engines, as with the first at 65 the emersion of the propelling screw and

with the latter at the disengagement of the agriculture implements the motor would doubtless run off and adjustment of the regulator is neither theoretically nor practically possible for such widely differing conditions 70 of use.

I claim:

1. The combination, with an internal combustion engine having a fuel pump of the piston type, said pump having an intake 75 passage and a discharge passage, of means forming a conduit connecting said intake and discharge passages, and means integral with the pump piston for controlling said conduit.

2. The combination, with an integral combustion engine having a fuel pump including a piston, said pump having an intake passage and a discharge passage, of means forming a conduit connecting said intake 85 and discharge passages, said pump piston formed to provide valve means controlling said conduit.

3. In a fuel pump for fuel injection combustion power engines having a closed injection nozzle, the combination of a pump piston, a suction valve, a delivery valve, means providing a communication between the delivery side of the delivery valve and the suction side of the suction valve, said pump piston formed to provide valve means controlling such communication.

4. In an internal combustion engine, a fuel pump having a piston, a suction valve, a delivery valve, means for injecting fuel into the engine, a conduit connecting said delivery valve with said means, a second conduit connected to said first mentioned conduit at a point between the delivery valve and such fuel injecting means and adapted to relieve the pressure on said first mentioned conduit at a predetermined time, said pump piston extending into and forming valve means controlling said second conduit.

5. In an internal combustion engine, a fuel pump having a piston provided with a groove, a suction valve, a delivery valve, a nozzle for injecting fuel into the engine, a conduit connecting said delivery valve with said nozzle, a second conduit connected to said first mentioned conduit to release the pressure in said first mentioned conduit at a predetermined time, said second conduit being normally blocked by said piston but being opened when said groove is brought into register with said second conduit.

6. In an internal combustion engine, a fuel pump having a piston, a suction valve, a pressure valve, a fuel injection nozzle, a pressure conduit connecting said pressure valve and said injection nozzle, said pump piston formed to provide an overflow valve connected to said conduit between the pressure valve and the injection nozzle, said overflow valve connected to the pump suction 130

- 5 pipe and adapted to be opened during the last part of the pump pressure stroke in order to return surplus compressed fuel from the pressure conduit to the suction pipe before the pump completes its pressure stroke.
7. In an internal combustion engine, a fuel pump having a piston, a suction valve, a pressure valve, a fuel injection nozzle, a 20 pressure conduit connecting said pressure valve and said injection nozzle, said pump piston formed to provide an overflow valve connected to said conduit between the pressure valve and the injection nozzle, said 25 overflow valve connected to the pump suction pipe and adapted to be opened during the last part of the pump pressure stroke in order to return surplus compressed fuel from the pressure conduit to the suction pipe 30 before the pump completes its pressure stroke, and means for regulating the operation of said overflow valve.
- 10 ton providing valve means connected to said conduit, said valve means normally operable to release the pressure in said conduit during the last part of the pressure stroke of the pump, and means for axially adjusting the 15 pump piston whereby the limits of the stroke of the piston are changed without changing the length of said stroke.
8. In an internal combustion engine, a

In testimony whereof I have hereunto affixed my signature.

FRANZ LANG.
